UNITED STATES PATENT OFFICE

LUC ROCHEFORT, OF NEW YORK, N. Y.

COLLAPSIBLE UMBRELLA

Application filed September 6, 1929. Serial No. 390,690.

This invention relates to umbrellas and more particularly to umbrellas especially adapted to emergency uses.

Heretofore in the art use has been made for emergency purposes of umbrellas constructed principally of paper or like substances but all of such constructions contain disadvantages such as the required use of wooden handles, wooden or steel frames, etc.

10 An object of the present invention is to provide a new, simple, efficient and inexpensive umbrella, especially adapted for emergency uses.

15 A further object of the invention is to provide an umbrella constructed principally of paper and like substances which is capable of being collapsed into a flat package.

20 In the practice of the present invention the difficulties heretofore experienced are overcome by constructing an umbrella, the cover portion of which is composed of a plurality of layers of paper so fastened together as to cause the grain thereof to overlap or cross for purposes of adding strength to the structure.

25 The cover may be in the shape of a flat circular piece of material so folded radially as to be collapsible into a substantially triangular shaped package. For purposes of strengthening the cover portion when in expanded position, use is made of a plurality of frame members which in collapsed position lie flat against the cover portion and which in expanded and assembled position serve as stays in the framework. In addition these 30 members are provided with portions which may be utilized as a handle for the umbrella.

35 Other features and objects of the invention will become apparent by reference to the following detailed description taken in connection with the accompanying drawings forming a part of the same wherein

40 Fig. 1 is a perspective view of an umbrella embodying the invention in collapsed and folded position;

45 Fig. 2 is a view of the underside of the device in flat position showing, in part, the cross grain relation of two laminations in the umbrella;

50 Fig. 3 is a section taken on the line 3-3 of Fig. 2;

Fig. 4 is a cross-sectional elevation of a device embodying the invention in expanded position; and

Fig. 5 is a view of the underside of the device in the position illustrated in Fig. 4.

Referring now to the drawings 10 indicates the cover of the umbrella, which cover is made up of a plurality of strips of paper or similar material 11 so arranged as to constitute a laminated structure. For purposes of 60 strength, the grain of the various strips of material 11 are made to cross each other. 11' is a second strip of material composing the laminated structure of the umbrella in which the vertical shade lines thereon indicate the cross grain of the material with reference to the grain of outer layer 11. The various strips may be pasted together or secured together in any desired manner. In order that the cover member 10 may be collapsed into a 70 substantially triangular shaped package as illustrated in Fig. 1 the member 10 is creased radially at a number of points as indicated by the lines 12.

For purposes of providing a frame for the 75 umbrella when in expanded position for use, a plurality of members 13 are secured to one side of the member 10 at spaced equidistant points. Each member 13 is composed of a portion 14 having an extension slightly off-set as indicated at 15 which portions 14 and 15 are secured directly to the surface of the member 10. Integrally formed with the portions 14 and 15 is another portion 16 which is in pivotal relation to these portions along 80 substantially the line indicated by line 17. Formed as an integral part of the portion 16 is a smaller portion 18 movable with respect thereto for forming a handle in the manner to be explained hereinafter. The outer end 90 of each portion 16 is provided with an opening 19 through which may be inserted a braid or other arrangement for fastening the various members together.

In the operation of the device let it be 95 assumed that the cover portion 10 has been spread out into a flat circle as indicated in Fig. 2. For the purpose then of properly expanding the umbrella into shape for use the various members 16 are folded toward the 100

center of the member 10 and secured together as illustrated in Figs. 4 and 5 by means of a brad 21 or any other suitable device. By so connecting these members together the cover portion 10 is contracted somewhat into substantially the shape of a cone with depressions at intervals along the surface thereof provided by alternate lines of creasing 12. After the members 16 have been secured together the various smaller members 18 may be folded to extend downward from the point of connection with the member 16 and collected together to constitute a short handle for the device.

If so desired a cord 22 may have one end thereof secured to substantially the center of the cover 10 and when the device is in the position illustrated in Fig. 4 the free end of this cord may be wrapped around the collected members 18 to strengthen the handle formed thereby. In addition to strengthening the handle the cord serves to properly expand the cover member 10 since some tension may be applied thereto.

With the complete device in flattened position as illustrated in Fig. 2 the same may be collapsed into a substantially triangular shaped package as illustrated in Fig. 1 by folding the same along the various lines of creasing 12. When completely folded a covering member 23 of thin paper or any other material may be slipped thereover for holding the same in this package shape. The collapsed device is then in position for marketing through sales machine or through any other desired agency.

From the foregoing it will be seen that the present invention provides an umbrella composed principally of paper which may be cheaply manufactured and sold for emergency uses. In practice it has been found that the frame member composed of the union of the various members 16 is sufficient to support the umbrella through violent storms. It is to be understood of course that the material of which the members 14, 15, 16 and 18 are constructed is of such substantial character as to add reenforcement to the device. If desired fiber or relatively stiff pasteboard may be used, the only requirement being that it shall be capable of folding into the position indicated in Fig. 4 and at the same time it must have sufficient rigidity to furnish the required strength to the device. It will furthermore be apparent that the arrangement provides a self-contained umbrella complete with frame and handle which umbrella can be collapsed into a small package and which can be expanded without the agency of further equipment such as wooden handles etc.

It is to be understood that the present invention is not to be limited to the illustrated embodiment but it is to be limited only by the scope of the following claims.

I claim:

1. A device of the character described comprising a substantially circular member, a plurality of semi-rigid strips secured thereto at spaced intervals, said strips having as parts thereof members foldable toward the center of said circular member and adapted to be connected together, said device also having additional foldable members forming a handle for the device when collected together. 70 75

2. A device of the character described comprising a substantially circular member provided with a plurality of radial creases, a plurality of flat reinforcing strips secured thereto at spaced intervals and extending radially from the center thereof, said strips having as integral parts thereof foldable members adapted to be secured together to form stays for the device and additional members foldable from said stays to form, when collected, 80 85 a handle for the device.

3. A device of the character described comprising a substantially circular member provided with a plurality of radial creases, a plurality of flat reinforcing strips secured thereto at spaced intervals and extending radially from the center thereof, said strips having as integral parts thereof foldable members adapted to be secured together to form stays for the device and additional members foldable from said stays to form, 90 95 when collected, a handle for the device, said circular member and the strips attached thereto being foldable into a flat substantially triangular shaped package. 100

4. A device of the character described comprising a substantially circular member composed of a plurality of layers arranged in cross-grain relation, said member being provided with a plurality of radial creases, a plurality of flat reinforcing strips secured thereto at spaced intervals and extending radially from the center thereof, said strips having as integral parts thereof foldable members adapted to be secured together to 105 110 form stays for the device and additional members foldable from said stays to form, when collected, a handle for the device.

5. A device of the character described comprising a substantially circular member, a plurality of semi-rigid strips secured thereto at spaced intervals, said strips having as parts thereof members foldable toward the center of said circular member, and means for securing said members together when folded 115 120 toward the center of the circular member.

6. A device of the character described comprising a substantially circular member, said member being provided with a plurality of radial creases, a plurality of flat re-enforcing strips secured thereto, one between each of said radial creases, and extending radially from the center thereof, said strips having as integral parts thereof members foldable toward the center of the circular member, and 125 130

means for securing the extremities of said foldable members together when the same are folded toward the center of said circular member.

5 In testimony whereof, I have signed my name to this specification.

LUC ROCHEFORT.
